UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHTING UNIT AND REFLECTOR THEREFOR.

Application filed September 2, 1924. Serial No. 735,248.

My invention relates to lighting units and reflectors. More in particular, the invention relates to that type of unit and reflector which is especially adapted for use in the field of highway lighting. Heretofore, lighting units have been provided with refracting elements for the purpose of controlling the light distribution of the unit. These refractor elements have usually been 10 in the form of prismatic glass elements. Elements of this type are quite expensive and also subject to fracture. I have found, however, that suitable light distribution may be produced with lighting units by using reflectors instead of refractors. Ordinarily, a reflector in a lighting unit would produce a dark background which would interfere with the illumination of the enclosing globe of the unit. I have found, however, that this objection can be avoided by providing a reflector with a large number of comparatively 20 small openings or perforations through which a small percentage of the flood of light within the area covered by the reflector may 25 sift through and light up the background of the reflector.

It is also an object of the invention to fill in the perforations with some transparent light diffusing material such as a lacquer or, 30 in some instances, glass, in order to avoid the formation of objectionable shadow outlines due to the perforations. The perforations in these reflectors may be designed to allow, for example, 10% of the light subtended by the 35 reflector to pass through.

The details of my invention are herein-after more fully set forth and claimed, reference being had to the accompanying drawings in which Fig. 1 shows the unit in elevation and partly in section, a perforated reflector being also shown; Fig. 2 shows one form of the perforation in perspective; Fig. 3 shows a plan and side view of another form of reflector; Fig. 4 is a section along the lower rim of the reflector of Fig. 2 showing how the rim may be serrated to avoid the formation of a sharp rim shadow on the globe or other background of the reflector; Fig. 5 is a section on $x-x$ of Fig. 4 showing the coat of transparent diffusing material such as a lacquer covering the perforations; and Fig. 6 is a section of a form of reflector in which a glass surface with protuberances is coated along the interstices or depressions 50 with a reflecting metal such as silver.

Referring more in detail to the drawings, it will be seen that the globe 2 encloses the light source 3 and is supported by the canopy 4. The globe is arranged to swing about any suitable form of hinge 5 and to be held in 60 closed position by any suitable form of latch 6. Within the unit there is provided a socket of any suitable type, not shown, for receiving the lamp 3. Within the globe there is provided a reflector 7 which has a 65 central opening through which the neck of the lamp 3 extends. About the lamp 3 there is provided one form that is an ellipsoidal form of perforated reflector 8 which may be secured in place in any suitable manner. As 70 shown, the upper rim 9 of the reflector is spun over the inner rim of the reflector 7 and is thus held in position. The construction of the reflector 7 is such that when the globe is unlatched and lowered about the hinge 5 75 the reflector 7 is permitted to settle until the perforated reflector 8 rests upon the lamp 3, which latter serves as support for both reflectors while the globe 2 is down. As the globe is raised and returned to its closed 80 position the outer rim of the reflector 7 engages the rim of the globe 2 and is thus picked up again and raised into position thereby bringing the perforated reflector 8 85 also into position. With this type of reflector the light passes through the perforations and falls on the outer enclosing globe 2 of the unit which is preferably of the diffusing type and which may also be of the ripple type. The light that passes through the 90 perforations, therefore, enables the outline of the globe to be seen at night. The diffusing lacquer 10 may be for example, glyptal. Or, as indicated in Fig. 6, it may be glass or any other suitable transparent medium. 95 The formation of any objectional shadow outlines due to the perforations can thus be avoided. The same result may be accomplished by the use of a reflector made of thin, blown or pressed glass having on the 100 outer surface prismatic elements such as beads, ripples or any other suitable form of prismatic protuberance 11 which will allow a small amount of light, 10% for example, to pass through. This light, of course, will 105 be over the inside of the globe and in this way avoid the formation of objectionable images of the perforations. The space between the prismatic protuberances may be first covered with a silver layer 12. A per- 110

forated mat is then applied over the reflector in such manner that the protuberances project through the perforations in the mat to enable the protuberances to be brushed clean of the silver deposit. The silver may be protected, as is well known, by a coat of paint or copper, lacquer or other protecting agent. In this way, the space between the protuberances remains silvered while the protuberances themselves are left clear for the purpose of allowing light to pass through which light is diffused over the surface of the enclosing globe.

It will be understood that the distribution of light may be varied by varying the shape of the reflector, which latter may have the form of the surface of revolution produced by rotating in any one of the conics. In fact, the surface of a reflector may assume the form of any curved surface about the axis of the unit.

A unit of the type contemplated may, therefore, be constructed to give any suitable type of light distribution about the axis of the unit, which distribution may be symmetrical or asymmetrical.

It will be understood that the principles of my invention may be applied in forms other than these specific concrete forms shown and described which will readily suggest themselves in view of the disclosure without departing from the spirit of the invention or from the scope of the claims herein.

What I claim as new and desire to secure by Letters Patent of the United States, is,—

1. A reflector consisting of a body of transparent material provided with a multiplicity of protuberances and a layer of a metallic reflecting material over the outer surface of said body through which the said protuberances project whereby rays of light from a source located within the reflector which strike the metal may be reflected back through the transparent material and whereby other rays of light may pass through the transparent material and through the protuberances beyond the reflector.

2. A reflector consisting of a body of transparent material provided with a multiplicity of protuberances and a layer of a metallic reflecting material over the outer surface of said body through which the said protuberances project whereby rays of light from a source located within the reflector which strike the metal may be reflected back through the transparent material and whereby other rays of light may pass through the transparent material and through the protuberances beyond the reflector.

3. A reflector consisting of a body of transparent material provided with a multiplicity of protuberances and a layer of a metallic reflecting material over the outer surface of said body through which the said protuberances project whereby rays of light from a source located within the reflector which strike the metal may be reflected back through the transparent material and whereby other rays of light may pass through the transparent material and through the protuberances beyond the reflector, the said reflector being in the form of an asymmetric surface of revolution whereby the reflected light is asymmetrically distributed about the axis of the reflector.

In witness whereof, I have hereunto set my hand this 26th day of August, 1924.

CROMWELL A. B. HALVORSON, JR.
